UNITED STATES PATENT OFFICE.

ORVILLE U. DESHA, OF FORT COLLINS, COLORADO, ASSIGNOR OF ONE-FIFTH TO THE
DESHA TYPELEX TRUST ESTATE, OF FORT COLLINS, COLORADO.

KEY ACTION FOR TYPEWRITING AND OTHER KEY-OPERATING MACHINES.

Application filed March 24, 1927. Serial No. 178,083.

My invention relates to key-action for typewriters and other type bar and key operating machines, actuating means at all times operatively connecting the type bar and key lever, 5 moving the type bar to printing point upon the depression of a key lever and means reversely breaking the said connection after the printing impact of the type bar for the return of the type bar to normal position while the 10 key lever is in depressed position; this general object being the subject matter of an application filed by me on November 5th, 1923, Serial No. 672,871, as a contradistinction between previous devices comprising a detachable connection or gap at some point between the key 15 lever and type bar after the latter has been given the movement necessary to effect the printing and before the key lever has completed its movement; and the present application providing means of the character 20 specified above which in the main is in the nature of another form of structure that may readily be incorporated in certain typewriting machines.

The drawings Figs. I, II, III and IV Sheets one and two show my invention embodied in a machine similar to the Remington standard typewriter and in which the invention may be readily incorporated by a slight modification 30 of structural features of the machine in effecting such incorporation. Figs. I^a, II^a, III^a and IV^a sheets three and four show my invention embodied in a machine similar to the Royal standard typewriter, a slight change in form of any of the corresponding parts such 35 as is shown by comparing the two sets of drawings accompanying this application is immaterial and it should be understood also that the invention is not restricted to use in 40 machines of the above type, but may be employed wherever found available.

The desired principle of operation, new mechanical functions, operative expedients, and other objects and advantages are herein- 45 after desired and are more particularly pointed out in the appending claims. In the accompanying drawing, wherein like reference characters indicate corresponding parts in the various views.

In the drawings Figures I and I^a each is a 50 vertical section of a typewriting machine, one key-action only being shown in normal position. Figs. II and II^a represent views of the key-mechanism similar to Figs. I, I^a the key- 55 lever being shown in a depressed position and

responding actuating the type bar. Figs. III, III^a also key mechanism similar to Figs. I, I^a, the key lever being shown in a depressed position and the type bar returned to its initial position. Figs. IV, IV^a is a skeleton view of 60 the key-mechanism for illustrative purposes in describing the mode of operation of the machine shown. It is understood, of course, that for the sake of clearness and to avoid complication of drawings the applicant has omitted to show or describe the remainder of key-levers and type bars as well as other devices necessary or advisable in the complete machine.

In the embodiment in Figs. I, and I^a, 1 70 indicates the frame of a typewriter—1 indicates the front and 1^b the rear, having a platen 5 carried by paper carriage not shown, 6 indicates one of the usual type-bars carrying type 7 at its front end, and having an operative connection 8 at the rear end, and is arranged to turn on pivot 9 in the form of a segment disposed vertically below frame face of the plate 10, thereby providing the type 7 with a common printing point A, as the type-bar 6 turns 80 on pivot 9 from the normal horizontal position of the rest on the segment 11; 12 indicates one of the key-levers carrying at the front end finger key 13, the rear end pivoted at 14 to bar 14^a in the rear of the machine, and is kept 85 normally in its elevated position by return spring 15 supported by bar 15^a, at normal rest the key-lever bearing against the under side of stop bar 15^b above the front part of the key-lever 12, in the usual manner.

Key-lever 12 is formed with an upward projection 16 and provides a rear saddle-backed seat 17 for the trip-link coupling hereinafter described.

The key-lever 12 is described as having two 90 incidents of operation, namely: the incident of depression and incident of release. The incident of depression is disclosed by the downward movement of key-lever 12 from radius B to radius C, and the incident of release is disclosed by the movement of key-lever 12 back from radius C to radius B. The type bar 6 is described as having two incidents of operation, namely the incident of response 95 and the incident of recoil. The incident of response of type-bar 6 is disclosed by the movement of the type-bar from its initial rest radius E to the printing point A, indicated by radius F, forming arc G from pivot 9. The incident of recoil of type-bar 6 is disclosed by 100 105 110

its movement from its printing point A back to normal rest E. These incidents of operation are, of course present in previous type-bar actions in so far as the incident of response 5 E to A of the type-bar 6 occurs simultaneously with incident of depression B to C, of key-lever 12, and the incident of recoil, A to E, of the type-bar occurs simultaneously with the incident of release, C to B, of the key-lever, 10 but my invention relates to later correlation of incidents of operation of the key-levers with that of the type-bar, in conforming to the operative expedient by which both the incident of response, E to A, of the type-bar 15 and incident of recoil, A to E, occur during the one incident of depression, B to C, of the key-lever.

In this case, the trip-link coupling peculiarly arranged between the key-lever and the 20 type bar accomplishes this operative expedient; the arrangement of said trip-link coupling being the subject matter of this application, hereinafter described.

18 indicates one of a series of vibratory 25 levers, corresponding in number with type bars 6 and key levers 12. Intermediately their ends the vibratory levers 18 are pivoted at 19 in a bar 20 extending across the machine. Means operatively connecting the type bar 6 30 and upper end of vibratory lever 18 may be the usual pin and slot connection 8, 8^a, Figs. I, II, and III or it may be the usual forward pull links 21^a Figs. I^a, II^a, III^a.

22 is a backward draw link and 23 is a 35 thrust link of what is described as a trip link coupling. The backward draw link 22 is pivoted at 25 intermediately of its ends to the lower end of the vibratory lever 18, and the rear end of the upward curved draw link 22 40 is pivoted at 24 to the rear end of the trip link 23, the forward end of the trip link 23 being pivoted at 26 to the upward projection 16 of the key lever 12.

The relative normal positions of pivots 24, 45 25 and 26 are engaged in a line nearly horizontal with the key lever 12 as shown by J J Figs. IV, IV^a, disclosing the trip link coupling to be horizontally disposed as distinguished from being engaged perpendicular to the key lever. It will be observed that the backward draw link 22 and the thrust link 23 constituting the trip link coupling operate 50 in a plane above the key lever, disclosing the invention to be overslung. Also, it will be noted that the backward draw link 22 and thrust link 23 operate behind the vibratory lever 18 disclosing the trip link coupling to be rearwardly engaged.

55 27 is a return spring the front end engaging the hole 27^a in the forward end of the backward draw link 22 and the forward end of return spring 27 engaging the hole 27^b in bar 30.

28 is an extended nose of the backward draw link 22 and is designated as a fulcrum trip nose, pivot 24 being the fulcrum point

about which the backward draw link 22 turns in cooperating with rear saddle-backed seat 17 on top of key lever 12 in tripping the thrust link 23 out of normal operative position.

The mechanical movements and operation thereof are the important factors in providing the function of the key-action. A further description of the operative principles therefore follows: The geometric circle H H

70 Figs. IV, IV^a with a horizontal diametrical line J J, from the backward pivot 24 to forward border pivot 25 circumscribes what is termed the actuating plane. The horizontal diametrical line J J crossing the actuating 75 plane, from the backward border pivot 24 to the forward border pivot 25 indicates the divert tension line and divides the actuating plane into an upper zone of response K and a lower zone of reaction L; the upper zone 80 of response K having to do with the response of the type bar 6 from radius E to radius F as the key lever 12 is being depressed from radius B to radius D; and the lower zone of reaction L having to do with the recoil of the 85 type bar 6 from the printing point A to radius E at rest as the key lever 12 is being continually depressed from radius D to radius C of depression.

The normal or idle position of the backward draw link 22 operates in the 90 upper zone of response K as shown in Figures I, II, III, IV, and I^a, II^a, III^a, IV^a. It is necessary that the backward draw link 22 and the thrust link 23 be relatively major and minor in length, and link 22 be in such form

95 and so engaged in hinge fold fashion so as to permit the pivotal point 26 to oscillate between the backward border pivot 24, and the forward border pivot 25 in crossing and recrossing the horizontal divert tension line J 100 J. In this case, the elements 22 and 23 of the trip link coupling are folded during the incident of depression from radius B to radius D of the key lever 12 simultaneously 105 with the incident of response of the type bar 110 6 from radius E to printing point A; and the hinge fold elements 22 and 23 unfold during the remainder of depression, radius D to radius C of key lever 12 simultaneously with the recoil of the type bar 6 from printing point 115 A back to radius E.

The rear saddle-backed seat 17 provided by the key lever 12 stops the backward border pivot 24 and effects operative tension lock of trip link 23 under influence of return spring 120 27 as the key lever 12 is being depressed from radius B to radius D. This tension lock of

thrust link 23 is also described as contractive tension lock meaning that while the key lever 12 is being depressed, the energy required to 125 respond the type bar 6 effects contractive pressure or thrust from pivot 26 to the backward border pivot 24 instead of expansive tension or pull.

The contractive tension of thrust link 23 stops its oscillation and this 130

link is moved bodily downward with the key lever 12, as shown in Figs. II and II^a the interior pivot 26 crosses the horizontal divert tension link JJ into the zone of reaction L. 5 Simultaneously with contractive tension lock of trip link 23, the backward draw link 22 operates under expansive tension between the backward border pivot 24 and the forward border pivot 25 while the key lever 12 is being 10 depressed from radius B to radius D to respond the type bar 6 from radius E to printing point A and the expansive tension of link 22 being relaxed while the key lever continues the incident of depression from radius 15 D to radius C and simultaneously with the recoil of the type bar 6 from the printing point A back to radius of rest E.

A change in relative positions of the backward border pivot 24 and the forward 20 border pivot 25 brings the interior pivot 26 down within the lower zone of reaction L thereby releasing the contractive tension lock of thrust link 23. The release of contractive tension lock of thrust link 23 permits it to re- 25 sume oscillation reversely breaking about the time the type impacts the printing point A. When the trip link coupling reversely breaks in the above manner there being no further obstruction to the recoil of the type bar 6, it 30 immediately recoils from A to E, while the key lever 12 continues its incident of depression from D to C and contacting with stop bar 34.

The dotted line M M indicates the correlative relationship of the border pivot and the interior pivot of the actuating plane during the process of operation, viz: Dotted line M M, Figs. I and I^a shows where the tri-pivotal relationship forms obtuse angle at the interior pivot 26 pointing upward within the upper zone of response during the normal position and effecting response of the type bar during the depression of the key lever 12. Dotted line M M, Figs. II, II^a shows the alignment of the border pivots and the interior pivot at the time the type bar completes its response or impact and begins to recoil. Dotted line M M, Figs. III and III^a shows the obtuse angle at the interior pivot 26 formed by the tri-pivotal relationship pointing downward within the zone of reaction as the type bar recoils.

22^a is an angular trip hammer provided near the front end of the backward draw link moving upward and communicating with the forward edge 18^a Figs. II and II^a of the vibratory lever as means for reversely breaking said coupling after the printing impact of the type bar for its return to normal position 55 while the key lever remains in depressed position. The underside of the trip hammer 22^a communicates with the upper edge 12^a (Figs. I and I^a) of key lever 12 thereby restoring the trip link coupling to normal operative position upon release of the key lever.

Variations may be resorted to within the scope of the invention, and portions of the improvements may be used without others.

What I claim as new and desire to secure by Letters Patent, is:

1. In a typewriting machine, a type bar, a key lever, actuating means at all times operatively connecting said type bar and key lever comprising a vertically disposed vibratory lever, a pivotal rod for said vertically disposed vibratory lever intermediately of its ends, means operatively connecting the vibratory lever and type bar, a trip link coupling comprising an upward curved draw link and thrust link at all times operatively connecting said key lever and vibratory lever for moving the type bar to the printing point upon depression of the key lever, means actuating said coupling to return the type bar after printing impact while the key lever is in depressed position, means restoring said coupling to normal operative position upon release of the key lever.

2. In combination, a type bar, a key lever, a segmental pivot rod therefore, actuating means at all times operatively connecting said key lever and type bar comprising a vertically disposed vibratory lever pivoted intermediately of its ends, means operatively connecting the vibratory lever and type bar, a trip link coupling comprising a backward draw link connected to the vibratory lever, a thrust link pivoted to said key lever intermediately of the ends of the latter and connected to said draw link—moving the type bar to printing point upon depression of the key lever, means reversely breaking said coupling after printing impact of the type bar, means returning the type bar to normal position while key lever is in depressed position, means restoring said coupling to normal operative position upon release of the key lever.

3. In a key-action for a typewriting machine, a type bar, a segmental pivot rod therefore, a key lever, actuating means at all times connecting said key lever and type bar comprising a vertically disposed vibratory lever, means operatively connecting the vibratory lever and type bar, a backward draw link operatively connected to said vibratory lever, a thrust link operatively connecting the backward draw link and key lever moving the type bar to printing point upon depression of the key lever, means reversely breaking said coupling after printing impact of the latter for return of the type bar to normal position while key lever is in depressed position, means restoring said coupling to normal operative position upon release of the key lever.

4. In a key action for key-operating machines, a key lever, a type bar, a backward draw link, a vertically disposed vibratory lever connected to the backward draw link, means operatively connecting the vibratory lever and type bar, a thrust link connected to

- the key lever, a backward border pivot connecting said thrust link and draw link, a saddle-backed seat provided by the top of the key lever for said backward border pivot, 5 said elements moving the type bar to printing point upon depression of key lever, means tripping said backward border pivotal point out of the saddle-backed seat reversely breaking said coupling after printing impact of 10 the type bar for returning the type bar to normal position while key lever is in depressed position, means restoring said forward border pivotal point to the saddle-backed seat upon release of said key lever.
- 15 5. In a type key action, a type bar, a key lever having an upward projection intermediately of its ends, actuating means at all times operatively connecting said key lever and type bar comprising a vertically disposed 20 vibratory lever, means operatively connecting the vibratory lever and type bar, a trip link coupling comprising a backward draw link and a thrust link pivoted to said upward projection provided by the key lever 25 moving the type bar to printing point upon depression of the key lever, means reversely breaking said coupling after printing impact of the type bar, means for the return of the type bar to normal position while key 30 lever is in depressed position, means restoring said coupling to normal operative position upon release of the key lever.
6. In a type key mechanism, a type bar, a key lever, an upward projection provided by 35 the key lever, a saddle-backed seat in the rear of said upward projection, actuating means at all times connecting said type bar and key lever comprising a backward draw link, a vertically disposed vibratory lever pivot- 40 otedly connected to the upward curved draw link, means operatively connecting the vibratory lever and type bar, a thrust link pivoted to the upward projection of the key lever and riding the saddle-backed seat moving the 45 type bar to the printing point upon depression of the key lever, means reversely breaking said coupling after printing impact of said type bar, means returning the type bar to normal position while key lever is in de- 50 pressed position.
7. In a type key action mechanism, a key lever, a type bar, actuating means at all times operatively connecting the key lever and type bar comprising a backward draw link, 55 a vertically disposed vibratory lever extending upwardly and downwardly from its pivot and connecting said draw link, means operatively connecting the vibratory lever and type bar, a thrust link connecting said backward 60 draw link and key lever moving bodily downward with said key lever upon depression of the latter responding the type bar to printing point, means limiting the downward movement of the backward end of said thrust link 65 reversely breaking said coupling after the

printing impact of the type bar for returning the latter to normal position while key lever is in depressed position, means for restoring the thrust link to normal operative position upon release of the key lever. 70

8. In a type key mechanism, a type bar, a key lever, an upward projection thereof, actuating means at all times operatively connecting said key lever and type bar comprising a vertically disposed vibratory lever, 75 means operatively connecting the vibratory lever and type bar, a trip link coupling horizontally disposed and engaged above the key lever backwardly of said vibratory lever, and compressing a backward draw link and 80 thrust link, a backward border pivot connecting the backward draw link and the thrust link above the key lever, a forward border pivot connecting the backward draw link and the vertically disposed vibratory lever 85 above the key lever, an interior pivot connecting the forward end of the thrust link and upward projection of the key lever, said elements moving the type bar to printing point upon depression of key lever, means re- 90 versely breaking said elements after the printing impact of the type bar returning the type bar to normal position while key lever is in depressed position, means restoring said elements to normal operative position upon 95 release of the key lever.

9. In a typewriting machine, a type bar, a key lever, an upward projection thereof, actuating means at all times operatively connecting said type bar and key lever comprising a vertically disposed vibratory lever, means operatively connecting the vibratory lever and type bar, a trip link coupling comprising a relatively long backward draw link and a relatively short thrust link pivoted to 100 the upward projection of the key lever and normally operating within a lower concavity of said draw link moving the type bar to the printing point upon depression of the key lever, means tripping said thrust link out 105 of the concavity of said backward draw link reversely breaking said coupling after the printing impact of the type bar for returning the type bar to normal position while the key lever is in depressed position, means re- 110 storing said thrust link to its normal operative position within the lower concavity of said backward draw link upon release of the key lever. 115

10. In a key action for a typewriting machine, a type bar, a key lever with an upward projection intermediately of its ends, actuating means at all times operatively connecting the key lever and type bar comprising a vertically disposed vibratory lever, 120 means operatively connecting the vibratory lever and type bar, a backward draw link, and a thrust link moving the type bar to printing point upon depression of the key lever, a backwardly extended fulcrum trip 125 130

- nose provided by the backward end of the backward draw link, a saddle-backed seat provided by the key lever in the rear of the upward projection of the latter cooperating with said fulcrum trip nose reversely breaking said coupling after the printing impact of the type bar, means restoring said coupling to normal operative position upon release of the key lever.
- 10 11. In a typewriting machine, a type bar, a key lever, actuating means at all times operatively connecting the type bar and the key lever comprising a vertically disposed vibratory lever, means operatively connecting the vibratory lever and type bar, a thrust link pivoted to the key lever, a backward draw link pivoted intermediately of its ends to the lower end of said vibratory lever and its backward end pivoted to the backward end of said thrust link moving the type bar to printing point upon depression of the key lever, a trip hammer provided by the forward end of the draw link communicating with the forward edge of the vibratory lever reversely breaking said coupling after printing impact of the type bar returning the latter to normal position while the key lever is in depressed position, the underside of said trip hammer communicating with the key lever restoring said coupling to normal operative position upon the release of the key lever.
- 15 12. In a recoil mechanism for a type key, a type bar, a key lever, actuating means at all times operatively connecting the key lever and the type bar comprising a vertically disposed vibratory lever, means operatively connecting the vibratory lever and type bar, a trip link coupling composed of a backward draw link and a thrust link, normal operative position of the elements of said coupling being folded—moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.
- 20 13. In a mechanical movement for a typewriting machine key, a key lever, a type bar, elements connecting said key lever and type bar comprising a vertically disposed vibratory lever, means operatively connecting the vibratory lever and type bar, a trip link coupling composed of a backward draw link and a thrust link, normal operative position of the elements of said coupling being folded—moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.
- 25 14. In a mechanical movement for a typewriting machine key, a key lever, a type bar, elements connecting said key lever and type bar comprising a vertically disposed vibratory lever, means operatively connecting the vibratory lever and type bar, a trip link coupling composed of a backward draw link and a thrust link, normal operative position of the elements of said coupling being folded—moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.
- 30 15. In a mechanical movement for a typewriting machine key, a key lever, a type bar, elements connecting said key lever and type bar comprising a vertically disposed vibratory lever, means operatively connecting the vibratory lever and type bar, a trip link coupling composed of a backward draw link and a thrust link, normal operative position of the elements of said coupling being folded—moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.
- 35 16. In a mechanical movement for a typewriting machine key, a key lever, a type bar, elements connecting said key lever and type bar comprising a vertically disposed vibratory lever, means operatively connecting the vibratory lever and type bar, a trip link coupling composed of a backward draw link and a thrust link, normal operative position of the elements of said coupling being folded—moving the type bar to printing point upon depression of the key lever, elements of said coupling unfolding reversely breaking said connection after the printing impact of the type bar returning the latter to normal position while key lever is in depressed position, means restoring the elements of said coupling to normally folded position upon the release of the key lever.

Signed at Fort Collins, in the county of Larimer and State of Colorado, this 1st day of December, A. D. 1926.

ORVILLE U. DESHA.
